UNITED STATES PATENT OFFICE.

PETER A. SNYDER AND GILSON HOMAN, OF JERSEY CITY, NEW JERSEY,
ASSIGNORS OF ONE-THIRD TO EDWIN MANNERS, OF SAME PLACE.

RAILWAY-CAR LABEL.

SPECIFICATION forming part of Letters Patent No. 431,290, dated July 1, 1890.

Application filed February 13, 1890. Serial No. 340,356. (No model.)

To all whom it may concern:

Be it known that we, PETER A. SNYDER and GILSON HOMAN, citizens of the United States, residing at Jersey City, in the county 5 of Hudson and State of New Jersey, have invented a new and useful Railway Index-Card, of which the following is a specification.

Our invention has reference to improvements in railway-car cards designed to represent whether a freight box-car, though closed, is loaded or empty. This is usually done at 10 present by the use of an ordinary paper card which is tacked on the car when closed and marked "Empty" or "Loaded," as the case may be; but this method is temporary and troublesome, requiring the use of a fresh or new card 15 at each loading or emptying of a car.

The objects of our improvement are to provide some convenient and inexpensive means 20 to indicate the condition of a closed freight-car which will be permanent and durable; in short, to furnish a metal car-card that may be affixed to any car and simply reversed as the empty or loaded condition of the same is 25 desired to be shown. We attain these objects by the means illustrated in the accompanying drawings, in which—

Figure 1 is a general view of our reversible index-card, showing both sides of the same. 30 Fig. 2 is another general view, where it is preferred to reverse the card by lifting it up and letting it down instead of turning it from side to side, as in Fig. 1.

Similar letters refer to similar parts.

Our reversible index-card is a rectangular plate A, made of sheet-iron or other metal, painted plain or in color, with the word "Empty" painted or lettered on one side and the word "Loaded" similarly stamped on the other or reverse side, as in the respective figures. The 35 card is fastened to the car by means of two ordinary staples s s, one foot of each passing

through the slots c c, near one edge of the card. These slots have sufficient play to allow the card A to turn on them and be reversed, 45 and also to be lifted up slightly, so that the eyelet-slot d, near the opposite edge of the card, may pass over the screw or bolt head b, and dropping back of it hold the card securely from being displaced, one end of the 50 slot being larger than the remainder or main portion, so as to pass over the head. To reverse the card, it is simply relifted over the bolt-head b and turned to the other side and there secured by a similar screw or bolt b, as 55 in Fig. 1, or lifted off the bolt b and allowed to drop down and be secured, as in Fig. 2.

What we claim as our invention, and desire to secure by Letters Patent, is—

1. In a railway reversible index-card, the 60 combination, with a plate A, having the slots c c near one edge and an eyelet-slot d near the opposite edge, one end of the eyelet-slot being larger than the other end, staples passed 65 loosely through the slots c c, whereby the card may be swung upon the staples as upon hinges, and screw or bolt heads upon the sides opposite the staples, whereby the card may be secured with either side out by causing the larger portion or end of the eyelet-slot to pass 70 over the head on one side or the other of the staples and causing the smaller portion of the slot to pass down behind the head, substantially as described.

2. In railway reversible index-cards, a metal 75 plate painted white or in color with the words "Empty" and "Loaded" stamped or lettered on its respective sides, substantially as described and illustrated.

PETER A. SNYDER.
GILSON HOMAN.
